UNITED STATES PATENT OFFICE.

ANDREW E. MILLER, OF BALTIMORE, MARYLAND, ASSIGNOR TO SOLOMON HIMMEL, OF BALTIMORE, MARYLAND.

DISPLAY-RACK.

1,274,182.

Specification of Letters Patent. Patented July 30, 1918.

Application filed April 21, 1914. Serial No. 833,457.

To all whom it may concern:

Be it known that I, ANDREW E. MILLER, a subject of the King of Great Britain, residing in the city of Baltimore and State of Maryland, have invented new and useful Improvements in Display-Racks, of which the following is a specification.

While the invention to be hereafter described, in its broadest scope and sense relates to devices and mechanisms consisting of a rotatable member in the nature of a holder, rack or support for things in general, bodily movable either in free or inclosed space, with, if desired, or necessitated by the requirements of each particular case, such additional means, as are suitable to either control, lock, limit, retard or set free the rotary or the bodily, or the rotary and bodily movements of the rotatable and bodily movable member or members, or both of them together; it more particularly pertains to such devices where for the support and display of articles of merchandise or goods a rotatable rack is employed which is movable within or to and from positions within to positions outside of an inclosed space or compartment such as a store display cabinet, with either solid or transparent walls, for the purpose of advantageously displaying, offering for sale, and readily and conveniently handling the goods.

In its still more limited sense, the invention relates to that class of rotatable bodily movable display devices in free or inclosed space where one or a number of horizontal longitudinal bars for carrying goods constitute part of the rotatable supporting member or members of the device which, if adjacent a wall, must be bodily moved as far therefrom as the distance between the center of rotation of the rotatable member and the outermost point upon its boundary to allow of complete rotation without any portions of the boundary of the member fouling the wall, and which if inclosed and to be rotated when still partially within said inclosure, normally rests within a case or cabinet, the greatest inside over all dimension of which must be equal to or exceed the greatest corresponding over all dimension of the space occupied by the goods, and in order to allow complete rotation in the case, the rotatable member must be bodily moved away from the rear wall of the case a sufficient dis-

tance as outlined above to prevent fouling of the rear wall. Such devices usually employ one or a number of bars symmetrically and equidistantly attached to a centrally hung, pivoted or otherwise rotatably arranged supporting member for the purpose of supporting and displaying articles such as meats, ready-made garments, or the like, placed on individual shiftable and partly rotatable hooks. Supporting and holding devices form no part of the present invention and may consist, as illustrating this invention, of two parallel bars similar in nature, structure and application to the well known traveling meat racks of slaughter and storage houses or to be more pertinent practically identical with those employed in wardrobes such as described in Patent Number 345,921, or to store or display cabinets of later construction and design, or may consist, if desired, of any old and well known form or arrangement. Mention of these bars is made here merely because their position either when stationary, in or out of the case, or when traveling from rear or front position, or vice versa, forms an essential and important part of this invention.

Now, as for the sake of appearance and convenience, in the first instance, it is desirable and advantageous to maintain parallelism between the bars and rear wall, or the front of the cabinet, when the former are not only at the forward or rearward position but also when they are being bodily moved into or out of the cabinet, as the case may be, and also because, in the second instance, should the goods be fragile and the rear wall of the cabinet of a flimsy or brittle material, such as light fabrics or glass, a deliberate or accidental turning of the rotatable rack to a greater or lesser degree at a point within the cabinet some distance removed from the point of its outer position, while being bodily moved, might result through fouling to the damage of either or both, therefore, one object of this invention is to so construct the rotatable member as to accomplish this desired result in a simple, logical and suitable manner either during its travel or when at rest.

It is also an object of this invention to provide a display rack in which parallel article carrying rods are rotatably supported upon a standard mounted for limited bodily travel in and out of a display case and in

- which the parallel article carrying rods are normally parallel with the front or rear walls of the case and are snugly received between the side walls with a slight clearance between them, and when in the outward position the rack is readily rotatable to display and make accessible the articles upon the rear. It is another object of this invention to so mount the rack that during bodily movement rotation of the article carrying means sufficient to cause it to strike the rear wall of the case is checked and fouling avoided when a force of normally sufficient strength to move the rack bodily is applied at its outer boundary, said force and checking means causing the rack to move bodily until the end of outer travel is reached at which point it may be rotated and retained against inward movement until it is returned manually or automatically to the normal positions. A further object of this invention is to so mount the rack that upon a partial rotation during the bodily movement or between certain points at the outer end of travel it will automatically be returned to the normal positions, the automatic returning means being rendered ineffective during rotation beyond these points. It is a still further object of this invention to so arrange the parts that when the rack is at the outer end of its travel means are provided so that a slight effort to rotate the rack through a partial revolution is only necessary to cause it to automatically continue its rotation thereby reversing the position of the rods from front to rear, maintaining it at that position and thus present the rear articles thereon to the customers. This automatic reversal of the normal position is a great convenience to the salesman and its automatic return or reversal after a slight rotation places it always in position to be moved bodily within the case without hindrance. A still further object of this invention is to arrange this construction so that the rack is bodily movable during the exertion of a slight continuous effort without rotation in the direction of travel upon any part of the rack, and if a sudden or mischievous jerk is given in pulling the rack outward instead of causing the rack to strike the rear wall of the case the rack will yield and right itself during the advance in the direction of the jerk. Figure 1 is an enlarged top plan view illustrating the rack mechanism. Fig. 2 is a view in transverse vertical section taken on the line 5—5, Fig. 1. Fig. 3 is a top plan view of a modified form of rack returning mechanism in detail. As previously stated the particular form or construction of that part of the rack for carrying the articles forms no part of this invention and can be of any desired form or construction mounted upon a rotatable mem-

ber as this invention relates to the mechanism by which the rack is operated to accomplish the results above set forth.

Referring to the drawing, the rack (not shown) is supported by a shaft 2, rotatably mounted upon a carriage 3, capable of limited transverse bodily movement within the case 4, so that the rack may be bodily moved within the case.

Guides 5 for the carriage are secured to the casing beneath the floor. The sides of the carriage and the adjacent guides are provided with complementary angular grooves, forming a race way for ball-bearings 6, supporting the carriage, as shown in patent numbered 991,164, greatly reducing friction during its travel as well as overcoming binding caused by an uneven weight or force exerted upon the rack. Stops are provided to limit the movement of the carriage at each end of the guides. The lower end of the rack supporting shaft is rotatably mounted in any desired manner upon the carriage and is provided with a positioning member 7, secured thereto adjacent the carriage and beneath the casing floor. The periphery of the positioning member, when in the form of a disk as shown in Figs. 2 and 4, is provided with oppositely disposed complementary angular or curved cut out portions 8, entering within the normal circumference of the disk.

A pressure member is yieldingly mounted upon the carriage to normally lie within the angular or curved portions of the disk, and adapted to exert force or active inward pressure against the periphery of the positioning member, and coact with the angular or curved portions thereof, to check the rotation of the shaft, when an external rotative force is applied thereto and to return or reverse the shaft to normal position upon the removal of said force.

The positioning member 7 is shown on Fig. 1 as being in the form of a disk with the oppositely disposed angular portions 8 arranged with the adjacent reentrant sides converging toward each other to form in effect a deep notch. The pressure member comprises a pressure roller 9, mounted upon an arm 10, pivoted at one end to the carriage, with its free end connected to a spring 11, secured to the carriage, whereby the roller at all times exerts an active pressure upon the positioning member. A partial rotation of the shaft will cause the roller to be moved outwardly against the tension of the spring, and cause it to ride upon the contacting angular portion of the positioning member, and upon the removal of the force causing rotation, the pressure member will coact with the positioning member to return the shaft and rack to normal position. When the carriage is in its outermost position the shaft will return to its normal

position upon the removal of any force sufficient to cause a partial rotation, and when the applied force is great enough to cause the roller to ride beyond the angular portion, and to be engaged by the circular circumference of the positioning member, as shown in dotted lines in Fig. 1, the automatic self-positioning action is rendered ineffective until the roller has traveled beyond 10 the circular circumference to the next angular portion, and then the rotation is automatically continued until the shaft and rack have been reversed.

The positioning member and pressure 15 member may be of any other form which will accomplish the same result.

Fig. 3 illustrates a form of positioning member 7¹ in which there is no dwell. The opposite sides are cut out on a curve concentric with the pressure roller 9¹ to engage the roller in normal position with the forward side extending in a straight line at a tangent to this curve from the point of engagement and the opposite side from the 25 point of engagement continuously curved away therefrom.

In reversing the rack in the outermost position, in this form, the operator normally takes hold of the right side and therefore 30 because of the short tangent of this form only a short rotative movement is necessary to cause the pressure roller to pass there- beyond on to the long curve which will automatically continue the rotation until the 35 rack is reversed.

In either form of the invention, if the carriage is free to move, a rotative force applied to the rack sufficient to cause a partial rotation of the shaft and corresponding 40 movement of the member, will be diverted through the pressure member into a bodily movement of the carriage in the direction of the force, and if the carriage be at its outermost position and the rotative force 45 be exerted in an outer direction, upon its removal after a partial rotation, the rack will be automatically returned to its normal position; but in the form of the invention illustrated in Fig. 3, if the force be 50 exerted long enough to cause a rotation of the positioning member, so that the outermost points of its periphery pass the pressure member, the rotation will be automatically continued and the rack reversed.

55 In order to provide means for avoiding rearward movement of the rack when in its outermost position and when not normally parallel with the case, and in order to provide additional safe guards and make the 60 construction more fool proof when operated by an inexperienced operator or salesman, a means for restraining the movement of the pressure member away from the positioning member is provided, the same decreasing in effect as the carriage moves out-

ward and so constructed as to allow at the outermost position of the carriage the pressure member to ride over the outermost points of the periphery of the positioning member and when so doing to prevent the 70 rearward movement of the carriage.

When rotated in its forward position it is often desirable to display the goods when the rack is in an angular position in relation to the case, the normal force is neutralized by the roller riding upon the circular portion of the positioning disk or when the spring-pressed member coacting with the rotatable member, in its modified form, is normally in contact with the corresponding face of said 80 member.

The restraining means is illustrated in the drawings as a flat spring 12 arranged vertically adjacent the normal path of the pressure roller 9 rigidly secured against transverse movement to the case or guide at any point between the innermost position of the pressure member and the rear wall of the case and at the forward end preferably secured by a pin and slot connection to a portion of the guide or forward wall of the case. The spring is laterally inclined and then extended at the outer end of the travel of the pressure member to follow adjacent its path during reversal of the rack. The 95 inclined portion of the spring acts as a stationary abutment upon an attempted inward movement of the rack when the pressure roller is pressed outward during a rotation of the rack in its outermost position. 100

The relations of the restraining member, pressure member and positioning member are such that a slight rotation of the rack is always possible during the bodily travel. The normal pressure exerted by the pressure member upon the positioning member is sufficient to prevent rotation of the shaft upon a continuous pull or push on any part of the rack in either inward or outward direction and a partial rotation during the 110 travel produced by a jerk will cause the pressure member to engage the restraining member and in such case the amount of rotation will be checked so that in no position during the travel can any portion of the rack 115 strike the rear wall of the case but on the other hand the jerk having occasioned a slight rotation the resilient restrain will cause the pressure member to coact with the angular or curved portion of the positioning member to move the carriage in the direction of the jerk. The restraining member is of sufficient strength to prevent the pressure member from riding beyond the angular or curved position of the positioning 120 member at any other point except when in the outermost position of the rack. The amount of restraint upon the pressure member decreases during outward movement of the carriage because as the rack approaches 125 130

its outermost position the amount of rotation without fouling the rear wall of the case increases.

From the above description it is readily seen that the main purpose of this invention is to provide ease of operation, minimum of resistance and maximum of convenience in handling without having recourse to rigid construction necessarily requiring complication of parts to produce the same result. While the preferred forms of this invention are illustrated and described, yet it is to be understood that detail changes may be made without departing from the scope thereof, and that the relative proportions of the parts may be changed without limiting the scope of the invention as claimed, or its useful application in other directions.

20 What I claim is:

1. In a display rack, a case, a carriage reciprocatable therein, a rotatable shaft thereon normally supporting article carrying arms parallel to the sides of the case, a positioning member upon the shaft, an active pressure member upon the carriage, a restraining member adjacent the path of the pressure member adapted to be engaged thereby upon a partial rotation of the shaft during travel and spaced apart from the pressure member at the outer end of travel to allow of the rotation of the shaft and provide an abutment for the pressure member against inward movement during such rotation.

2. In a display rack, a case, a carriage reciprocatable therein, a rotatable shaft thereon normally supporting article carrying arms parallel to the sides of the case, a positioning member upon the shaft, a pressure member upon the carriage coacting with the positioning member to return the shaft to

normal position upon a partial rotation and means to reverse the position of the rack from rear to front upon a slight rotation of 45 the rack in its outermost position.

3. In a display rack, a case, a carriage reciprocatable therein, a rotatable shaft thereon normally supporting article carrying arms parallel to the sides of the case, a positioning member upon the shaft, an active pressure member upon the carriage coacting with the positioning member to return the shaft to normal position upon a partial rotation, and a resilient restraining member 50 coacting with the pressure member upon a partial rotation of the shaft during travel to return the shaft to normal and advance the carriage and means to reverse the position of the rack from rear to front upon a 55 slight rotation of the rack in its outermost position.

4. In a display rack, a case, a carriage reciprocatable therein, a rotatable shaft thereon normally supporting article carrying 60 arms parallel to the sides of the case, a positioning member upon the shaft, an active pressure member upon the carriage, a resilient restraining member adjacent the path 65 of the pressure member adapted to be engaged thereby upon a partial rotation of the shaft during travel and spaced apart from the pressure member at the outer end of travel to allow of the rotation of the shaft and provide an abutment for the pressure 70 member against inward movement during such rotation and means to reverse the position of the rack from rear to front upon a slight rotation of the rack in its outermost position.

ANDREW E. MILLER.
